(57) **CLAIM**

The ornamental design for a sanding tool, as shown and described.

DESCRIPTION

FIG. 1 is a top perspective view of a sanding tool showing our new design, the sanding tool being shown with its fasteners in a closed position.

FIG. 2 is a right elevational side view thereof.

FIG. 3 is a left elevational side view thereof.

FIG. 4 is a front elevational view thereof.

FIG. 5 is a rear elevational view thereof.

FIG. 6 is a top plan view thereof.

FIG. 7 is a bottom plan view thereof; and,

FIG. 8 is another top perspective view thereof, the sanding tool being shown new with its fasteners in an opened position.
